CLAIM

I claim the ornamental design for a game board, as shown and described.

DESCRIPTION

FIG. 1 is a perspective view of a game board in accordance with the present design;

FIG. 2 is a front elevation view thereof.

FIG. 3 is a back elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines shown in the drawings represent portions of the game board that form no part of the claimed design.

1 Claim, 7 Drawing Sheets
